US00D533452S

(12) **United States Design Patent** (10) **Patent No.:** **US D533,452 S**
(45) **Date of Patent:** **** Dec. 12, 2006**

(54) **CLOSURE FOR A CONTAINER**

(75) Inventor: **William C. Vogel**, Mequon, WI (US)

(73) Assignee: **Gateway Plastics, Inc.**, Mequon, WI (US)

(**) Term: **14 Years**

(21) Appl. No.: **29/217,727**

(22) Filed: **Nov. 20, 2004**

(51) **LOC (8) Cl. 09-07**

(52) **U.S. Cl. D9/449; D9/447**

(58) **Field of Classification Search** D9/450, D9/449, 447, 445, 440, 438, 435, 434; D7/596, D7/591; D32/29.1; 222/556, 546, 498, 480; 220/254.1-254.9, 835, 253; 215/344, 253, 215/245, 237, 235, 216

See application file for complete search history.

(57) **CLAIM**

We claim the ornamental design for a closure for a container, as shown and described.

DESCRIPTION

FIG. 1 is a top perspective view of a closure for a container; FIG. 2 is a top perspective view of the design of FIG. 1; FIG. 3 is a bottom perspective view of the design of FIG. 1; FIG. 4 is a bottom perspective view of the design of FIG. 1; FIG. 5 is a top view of the design of FIG. 1; FIG. 6 is a bottom view of the design of FIG. 1; FIG. 7 is a right side view of the design of FIG. 1, the left side view being a mirror image; FIG. 8 is a front view of the design of FIG. 1; FIG. 9 is a rear view of the design of FIG. 1; FIG. 10 is a top perspective view of the design of FIG. 1 illustrating the flaps in an open position; FIG. 11 is a top perspective view of the design of FIG. 1 illustrating the flaps in an open position; FIG. 12 is a left side view of the design of FIG. 1 illustrating the flaps in an open position; FIG. 13 is a right side view of the design of FIG. 1 illustrating the flaps in an open position; FIG. 14 is a bottom view of the design of FIG. 1 illustrating the flaps in an open position; and, FIG. 15 is a top view of the design of FIG. 1 illustrating the flaps in an open position.

The broken lines in the drawings are for illustrative purposes only and form no part of the claimed design.

1 Claim, 12 Drawing Sheets
